Primary Examiner — Mitchell I. Siegel

(57) **CLAIM**

The ornamental design for a golf mat, as shown and described.

DESCRIPTION

FIG. 1 is a top plan view of the golf mat showing our new design;

FIG. 2 is a bottom plan view thereof;

FIG. 3 is a front elevational view thereof;

FIG. 4 is a back elevational view thereof;

FIG. 5 is a left-side elevational view thereof;

FIG. 6 is a right-side elevational view thereof;

FIG. 7 is another top plan view thereof, the broken line showing of the remainder of the mat being a different shape.

FIG. 8 is a bottom plan view of FIG. 7;

FIG. 9 is a front elevational view of FIG. 7;

FIG. 10 is a back elevational view of FIG. 7;

FIG. 11 is a left-side elevational view of FIG. 7; and,

FIG. 12 is a right-side elevational view of FIG. 7.

The broken lines in the figures show portions of the design that form no part of the claimed design.

1 Claim, 12 Drawing Sheets
